UNITED STATES PATENT OFFICE.

WILLIAM RILEY BALLOU, OF SOMERSET, KENTUCKY.

RAILWAY.

Application filed January 6, 1923. Serial No. 611,125.

To all whom it may concern:

Be it known that I, WILLIAM R. BALLOU, a citizen of the United States, residing at Somerset, in the county of Pulaski and State of Kentucky, have invented a new and useful Improvement in Railways, of which the following is a specification, reference being had to the accompanying drawing.

This invention relates particularly to such railway tracks as are used in mines and similar situations for the operation of relatively small cars.

The object of the invention is to provide convenient and efficient means for securing the track rails and to provide efficient means for shifting the rails at a switch in such a track.

In the accompanying drawings,

Fig. 1 is a plan of a track structure embodying a switch built according to my invention;

Fig. 2 is a transverse section on the line, 2—2, of Fig. 1, looking toward the left;

Fig. 3 is a transverse section on the line, 3—3, of Fig. 1, looking toward the left;

Fig. 4 is a transverse section on the line, 4—4, of Fig. 1, looking toward the left;

Fig. 5 is a section parallel to the main track, on the line, 5—5, of Fig. 1, looking in the direction of the arrow;

Fig. 6 is a transverse section on the line, 6—6, of Fig. 1, looking toward the left;

Fig. 7 is a transverse section on the line, 7—7, of Fig. 1, looking toward the left;

Fig. 8 is a transverse section on the line, 8—8, of Fig. 1, looking toward the left;

Fig. 9 is a transverse section on the line, 9—9, of Fig. 1, looking toward the left;

Fig. 10 is a section parallel to the branch track, on the line, 10—10, of Fig. 1, looking in the direction of the arrow;

Fig. 11 is a section on the line, 11—11, of Fig. 1, looking toward the right;

Fig. 12 is a horizontal section on the line, 12—12, of Fig. 3.

Referring to said drawings, A and A¹ are the two rails of a main track. B and B¹ are fixed sections of branch track rails. B² is a "point" branch track rail section extending from the section, B¹, to the side of the main track rail, A¹. B³ is a movable "point" branch track rail section located between the rails A and A¹. The right hand ends of the rails, A and B, rest on a tie, T, of any form. The drawings show the other ties, C, D, E and F, of special form. The

body of each such tie is of metal and channel-shape, the two flanges being directed downward.

At a distance from the middle, upright plane of the main track less than the distance of the main line track rails from said plane, each flange of the tie, C, is provided with a horizontal slot, C³. A bolt, C⁴, extends transversely across the tie and through each slot. At each outer side of the tie and at each rail, A and A¹, a locking rod, C⁶, having a hook at each end engages said bolt and the outer edge of the foot of the adjacent rail, A or A¹. The opposite edge of the foot of the rail is engaged by a plate, C⁷, secured to the upper face of the tie by bolts or rivets, C⁸. A wedge-form key, C⁹, is brought into the slot, C³, between each bolt, C⁴, and the adjacent end of the tie to drive the bolt toward the middle of the tie, whereby the locking rod, C⁶, is put under tension to force the adjacent rail against the plate, C⁷.

At the ties, D and E, the rails, A and A¹, are similarly secured by means of rods, C⁶, and plates, C⁷.

The point section, B³, is pivoted to the tie, C, by means of a plate, B⁴, secured to said rail by means of a bolt or rivet, C²; and resting on the plate, C⁷, and loosely secured thereto by means of an upright bolt, C¹, extending through the plate, B⁴, and the plate, C⁷, and the upper wall of the tie. The point sections, B² and B³, are coupled to each other, near the points, by a bar, B⁵, extending under the main track rail, A¹. At each point, an angle plate, B⁶, has one arm secured against the side of the adjacent point by bolts or rivets, B⁷, while the other arm rests flatwise on the bar, B⁵, and is rotatably secured thereto by an upright bolt, B⁸, extending through the angle plate and the bar, B⁵.

The opposite end of the point rail section, B², rests on the tie, F, and is there engaged by a plate, C⁷, and a locking rod, C⁶, such engagement being loose enough to allow the slight turning movement that is needed to allow the point of said section to move into contact with the adjacent face of the main track rail, A¹. The rail branch section, B², is similarly engaged on the tie, D, by a plate, C⁷, and locking rods, C⁶. On the tie, C, the branch rail section, B², is free, resting slidably on the upper face of said tie.

The branch track rail, B¹, is secured to the tie, F, by means of the plate, C⁷, and a

locking rod, C⁶, at that side of the tie. The end of the branch track rail, B, adjacent the main track rail, A¹, is secured upon a metal plate or casting, G, which is seated on the tie, F, at the outer side of the main track rail, A¹, and suitably secured to said tie, as by means of bolts or rivets, G¹. Said end of the rail, B, is made higher than the rail, A¹, such difference in height equalling the thickness of the adjacent end of the point rail section, B³. At the side of the rail, B, toward the rail, B¹, and separated therefrom by a channel wide enough for the passing of a wheel flange is an upward-directed flange, G². Between said flange and the rail, B, on the one hand and the rail, A¹, on the other hand is sufficient space for the passing of a wheel on the rail, A¹.

Fig. 1 shows the switch set for the passing of a car on the main line track. The dotted lines on said figure show the point rail sections, B² and B³, shifted into position for the passing of a car to and from the branch line track. When the branch line track is to be used, the end of the point rail section, B³, adjacent the main track rail, A¹, is to be moved upward and across the rail, A¹, into alignment with the adjacent end of the branch line, B. That movement involves the turning of the section, B³, on the pivot formed at the bolt, C¹, whereby the point of the section, B³, is moved against the inner face of the main track line rail, A. This involves the endwise shifting of the bar, B⁵, whereby the point of the rail section, B², is brought against the outer face of the main track rail, A¹.

For shifting the point rail section, B³, a lever, H, is pivoted between its ends on a shaft, H¹, extending horizontally through the tie, E, below the upper wall of the tie. The upper end of said lever extends through a slot, E¹, in the upper tie wall and is coupled to a bracket, H², secured to the outer side of the rail section, B³. The position of the shaft, H¹, and the length of said lever above said shaft are such as to lift the rail section, B³, into position across the main rail, A¹, when the lever, H, is turned to move its upper end toward the rail, A¹, and to allow the rail section, B³, to rest on the tie, E, when the switch is in the open position. The lower end of the lever, H, is coupled to one end of a horizontal bar, H³. The opposite end of said bar is coupled to a hand lever, H⁴, which is pivoted at, H⁵, to an extension, E², of the tie, E. The distance between the pivot, H⁵, and the point at which the bar, H³, is coupled to the lever, H⁴, is such as to allow the lever, H⁴, to lie in the horizontal or a little below the horizontal position at one side of its pivot when the rail section, B³, is in the open position and to be in the horizontal or a little below the horizontal position at the other side of its pivot when

the rail section, B³, is in the closed position. Thus said lever and the bar, H³, are adapted to hold the lever, H, and the rail section, B³, in either the open or the closed position after the parts have been set by an attendant.

A supporting plate, C⁰, is placed under the rail, B³, on the tie, D. The part of said plate which is toward the rail, A¹, is higher than the part on which the rail, B³, rests when the switch is open. Thus the rail, B³, is given support when it is in either position.

A fixed guard rail, I, is placed parallel to the rail, B². Said guard rail engages the flanges of passing car wheels and resists tendency of said wheels to move on straight lines. Thus lateral pressure by the car wheels on the adjacent end of the inner movable rail, B, is avoided.

I claim as my invention,

1. In a railway, the combination of main track rails, fixed branch track rails located beside the main track, two movable branch track rails, the first located between the main track rails and the second being located outside the main track rails and said movable rails being pivoted on upright axes to permit horizontal sidewise movement of the points of said rails and to permit the opposite end of said first movable rail to be moved across the adjacent main track rail, and operator-controlled means for simultaneously moving said movable rails on their pivots, substantially as described.

2. In a railway, the combination of main track rails, fixed branch track rails located beside the main track, two movable branch track rails, the first located between the main track rails, and the second being located outside the main track rails and said movable rails being pivoted on upright axes to permit horizontal sidewise movement of the points of said rails and to permit the opposite end of said first movable rail to be moved across the adjacent main track rail, the pivot of the second movable rail being adjacent the end of the adjacent fixed track rail, and operator-controlled means for simultaneously moving said movable rails on their pivots, substantially as described.

3. In a railway, the combination of main track rails, fixed branch track rails located beside the main track, two movable branch track rails, the first located between the main track rails and the second being outside the main track rails and the first of said movable rails being pivoted between its ends on an upright axis and the second movable rail being pivoted adjacent the end of the adjacent fixed track rail to permit horizontal sidewise movement of the points of said rails and to permit the opposite end of said first movable rail to be moved across the adjacent main track rail, and operator-controlled means for simultaneously moving

said movable rails on their pivots, substantially as described.

4. In a railway, the combination of main track rails, fixed branch track rails located 5 beside the main track, two movable branch track rails, the first located between the main track rails and the second being located outside the main track rails and said movable rails being pivoted on upright axes 10 to permit horizontal sidewise movement of the points of said rails and to permit the opposite end of said first movable rail to be moved across the adjacent main track rail, means coupling the points of said movable rails, and operator-controlled rail-moving means applied to the end of the first movable rail at its end opposite the point, substantially as described.

5. In a railway, the combination of main 20 track rails, fixed branch track rails located beside the main track, two movable branch track rails, and operator-controlled means for moving the points of said movable rails sidewise and for moving the opposite end 25 of one of said rails in an arc into and out of position above the adjacent main track rail, substantially as described.

6. In a railway, the combination of main track rails, fixed branch track rails located 30 beside the main track, two movable branch track rails, the first located between the main track rails and the second being located outside the main track rail and said movable rails being pivoted on upright axes 35 to permit horizontal sidewise movement of the points of said rails and to permit the opposite end of said first movable rail to be moved across the adjacent main track rail, operator-controlled means for simultaneously moving said movable rails on their pivots, and a fixed guard rail between the outer movable rail and the adjacent main track 40 rail, substantially as described.

7. In a railway, the combination of main track rails, fixed branch track rails located 45 beside the main track, two movable branch track rails, the first located between the main track rails and the second being located outside the main track rails and said 50 movable rails being pivoted on upright axes to permit horizontal sidewise movement of

the points of said rails and to permit the opposite end of said first movable rail to be moved across the adjacent main track rail, the pivot of the second movable rail 55 being adjacent the end of the adjacent fixed track rail, operator-controlled means for simultaneously moving said movable rails on their pivots, and a fixed guard rail between the outer movable rail and the adjacent main track rail, substantially as described.

8. In a railway, the combination of main track rails, fixed branch track rails located 60 beside the main track, two movable branch track rails, the first located between the main track rails and the second being located outside the main track rails and the first of said movable rails being pivoted between its ends on an upright axis and the second movable rail being pivoted adjacent the end of the adjacent fixed track rail to 65 permit horizontal sidewise movement of the points of said rails and to permit the opposite end of said first movable rail to be moved across the adjacent main track rail, operator-controlled means for simultaneously moving said movable rails on their pivots, and a fixed guard rail between the outer 70 movable rail and the adjacent main track rail, substantially as described.

9. In a railway, the combination of two main line rails, two fixed branch line rails placed outside the main track rails and one being higher than the adjacent main track rail, two movable branch line rails the first being outside the main track rails and the second being between the main line rails and pivoted between its ends, a bar coupling the point ends of the branch line rails, and shifting mechanism in operative relation with the second branch line rail to move its end which is adjacent the high fixed branch line rail across the adjacent main line rail and into and out of alignment with said high rail, substantially as described.

In testimony whereof I have signed my name, this 28th day of December, in the year one thousand nine hundred and twenty-two.

WILLIAM RILEY BALLOU.
